WATER SLED

Fred L. Churchman, 1331 Colusa, Vallejo, Calif., and
Joseph L. Garske, 190 W. I St., Benicia, Calif.

Filed July 24, 1961, Ser. No. 66,022

Term of patent 3½ years

(Cl. D71—1)

FIG. 1 is a perspective of a water sled showing our new design.

FIG. 2 is a side elevation the opposite side being substantially the same.

FIG. 3 is a top plan view.

FIG. 4 is a bottom plan view.

FIG. 5 is a front elevation.

The flexible extensions of the handle are shown in varying positions in FIGS. 1 and 3.

We claim:

The ornamental design for a water sled, as shown and described.
